UNITED STATES PATENT OFFICE

ROBERT REÜTER, OF OFFENBACH-ON-THE-MAIN, GERMANY, ASSIGNOR TO SCHUFAB-
RIK HASSIA A.-G., OF OFFENBACH-ON-THE-MAIN, GERMANY, A CORPORATION

EDGE-FOLDING MACHINE

Application filed July 2, 1928, Serial No. 289,924, and in Germany January 30, 1928.

In the known machines for folding over the edges of leather and similar materials, as for shoe straps or the like, the strip of leather having a bevelled edge, for instance, is guided against a turning up tool while at the same time a hammer, acting from above, turns the bent up edge completely over and presses the same down. To the hammer a so-called guide is attached having a sharp edge which effects the folding of the material particularly at curves. The leather strip is held securely by a material-presser and is fed by a conveyor device. With such machines, however, it is possible only to fold over straight edges or only slightly outwardly curved edges of the material whereas a sharply rounded part, particularly at the end of a shoe strap could not be folded at all. Such sharply curved parts have, therefore, had, as previously, to be folded over by hand, an expensive and time-consuming operation.

The present invention relates to a machine for this purpose enabling even sharply curved edges of leather strips to be folded over and, moreover, to be turned out perfectly cleanly and with uniform disposal of the separate folds. In this manner the work is simplified extremely and the whole shoe strap may be folded over all around in the machine. This is achieved by various modifications of the tools of the machine. First of all the edge set up by the turning up device is prevented from being turned over by the hammer for any considerable length by the provision of a stretching hook on the turning up tool. The bent up edge of the leather lies between said stretching hook and the turning up device and is held by both so that only the part of the edge directly in front thereof can be turned over by the hammer. Also the hammer is so shaped as to extend, in the form of an arc around the guide device mounted rotatably on it, close up to the turning up device so that said hammer always encounters the edge of the leather and turns the same down even when operating on a considerable bend in the edge of the strap. The guide device is similarly placed close up against the turning up device to enable it to lay the material emerging from the turning

up device in appropriate folds. For this purpose the guide is bent somewhat towards the stretching hook.

It is, furthermore, necessary to bend the material pressing device more sharply than hitherto towards the turning up device so that the operator serving the machine may allow his fingers, holding the work, to approach closer to the tools and thus execute the rotation of the work necessary at sharp bends therein. In order to ensure that the operator shall be even less hindered by the material presser from effecting said rotation precisely at such points it appears preferable to dispose the rear portion of the material presser higher above the operating plate of the machine and to allow only the forward portion to come in contact with the plate or with the work.

Furthermore the support carrying the incision cutter necessary for the folding over of convex curves in the work is constructed without the arch previously provided thereon in order that it and the cutter may be taken closer to the turning up device and all the tools arranged closer together. The feed foot is also made correspondingly narrower.

It is possible with this construction to fold over even sharp curves without any difficulty.

One embodiment of such a machine is illustrated by way of example in the accompanying drawings in which:

Fig. 1 is a plan view from above;

Fig. 2 is a front elevation,

Fig. 3 is a side elevation and

Figs. 4 and 5 views from above and from one side respectively of the turning up device and the stretching hook mounted thereon and of the work held thereby.

The work 1 to be folded over is flattened or bevelled at the edge to facilitate its folding. In Figs. 4 and 5 the bevelled edge is shown unfolded at 2 and folded at 3. The folding tool consists of the turning up device 4 to which a stretching hook 5 is secured by means of a screw 5^a. The hook extends over and beyond the front edge 6 of the turning up device to such an extent that a gap corresponding approximately to the thickness of the edge of material to be folded

over is left between said edge 6 and said hook. The hammer 7 for pressing down the edge of the work has a reciprocating motion and carries a so-called folder 9 mounted rotatably on a pivot 8 and adapted to be brought into a predetermined position relatively to the hammer by a rod 10 which engages by means of a forked portion 11 on a pin 12 on said folder. The extent of movement of the folder 9 may vary in accordance with the movement of the rod 10. The hammer 7 is also furnished with an extension 13 the end of which projects to a position close in front of the turning up device 4 in order that the hammer shall still encounter the work-edge to be folded over even at sharp curves in said work. This extension 13 also embraces the folder 9.

The material pressing device 14 has a supporting arm 15 which is firstly disposed closer to the turning up device than hitherto and secondary is bent away upwardly as is clear in particular from Fig. 2 in which said material presser is illustrated in the raised position. The disposal of the presser arm nearer to the turning up device and above the operating plate 16 of the machine enables the operator to bring his fingers closer to the folding tools than he was previously able to do and thus to hold and rotate the work properly when a sharply bent edge thereof is being folded over.

In order not to interfere with the rotation of the work when folding over a sharply bent or curved edge the surface 17 of the feed device 18 contacting with the work is made substantially smaller than hitherto. Also the guide 19 determining the width of the edge to be folded over is brought closer to the turning up device. This is made possible by constructing the so-called cutter support 20, which was hitherto provided with an arch intended to assist the turning up device in the folding over of the edge, without said arch. It is also possible to make narrower than heretofore the incision cutter 21 which effects the incision of the work edge, when an inwardly curved edge is to be folded over, with the aid of the sharp edge 22 of the cutter support.

The machine operates in the usual manner, the work being held by the work presser 14 and fed forward on the plate 16 by the conveyor device 18; the work runs in a known manner over a roll 23 which projects through a corresponding opening in said plate 16. The bevelled edge 2 of the work 1 is set up by the turning up device 4 and is held in this position by the stretching hook 5. The latter is primarily of importance when a sharply curved portion of the work, say the front sharply curved end of a shoe strap, is being folded over. The hammer 7 is moved rapidly up and down in a vertical direction and its extension 13, which moves close behind

the turning up device, presses the leather edge downwardly. The folder 9 pivoted to said hammer is swung sharply towards the stretching hook by means of the rod 10 to fold the leather edge to the hammer. Said folder which is preferably bent towards the stretching hook somewhat forces the leather downwardly and lays it in the correct fold while the extension 13 of the hammer 7 presses securely on or strikes the bent over leather.

Since the work presser is bent round more sharply and its support 15 is also disposed higher than hitherto, the worker can allow his fingers to approach the tool more closely and thus effect the rotation of the work at a sharp bend which was not possible until now.

The machine is naturally operated at a lower speed during folding over of a sharp bend or curve at, say, the end of a shoe strap or other work and the feed is also shortened at this point in order that the folds may follow one another smoothly and uniformly.

In certain circumstances the stretching hook secured to the turning over device may also be obviated particularly when the curvature at strap ends, for example, of the leather is not too sharp; said stretching hook is, however, of the greatest advantage for completely smooth and uniform folding over of the work.

What I claim is:

1. A machine for folding over the edge of a piece of flat material, such as a leather strap, comprising in combination a turning-up device, a guide and a hammer having an extension embracing said guide, which is mounted on said hammer, and adapted to press the edge of the work downwardly in the close vicinity of said turning-up device, thereby enabling even sharply curved work to be folded over by the machine.

2. A machine as claimed in claim 1, and a stretching hook mounted on the turning-up device and adapted with the aid of the turning-up device to hold the bent up edge of the material.

3. A machine as claimed in claim 1, and a work presser, a supporting arm of the work presser disposed close to the tool and bent upwardly substantially as and for the purpose set forth.

4. A machine as claimed in claim 1, and an unarched cutter support constructed in order not to hinder the work from being sharply rotated and to enable the guide to be brought nearer to the tool.

5. A machine as claimed in claim 1, a stretching hook and a folder mounted on the hammer, bent toward the stretching hook and whose extent of movement may be varied.

6. A machine for folding over the edge of flat material comprising in combination a

turning-up device, a hammer having a hook-shaped operating end close to the device and a guide pivoted on the hammer and operating within the hooked portion close to the guide.

5 7. A machine for folding over the edge of flat material, comprising in combination a turning-up device, a hammer having a hooked end, a stretching hook adjustably mounted on the turning-up device, an unarched cutter support and a narrow cutter adjacent said device and cooperating with said support.

10 In testimony that I claim the foregoing as my invention, I have signed my name.
